(57) **CLAIM**

The ornamental design for a decorative dog pack with multiple pockets, as shown and described.

DESCRIPTION

FIG. 1 is a perspective view of a decorative dog pack with multiple pockets showing my new design;
FIG. 2 is a left elevational view thereof;
FIG. 3 is a right elevational view thereof;
FIG. 4 is a front elevational view thereof;
FIG. 5 is a top plan view thereof;
FIG. 6 is a top plan view thereof in a fully opened condition;
and,
FIG. 7 is a bottom plan view thereof in a fully opened condition.
The dashed lines in the drawing views represent stitching which forms part of claimed design.

The dog depicted by broken lines in FIG. 1 has been shown to illustrate environment and forms no part of the claimed design.
